CLAIM

The ornamental design for a case for electronic devices, as shown and described.

DESCRIPTION

FIG. 1 is a perspective view of a case for electronic devices showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is an exploded view thereof in which the components of the case are shown separated for clarity of disclosure.

The broken line showing of environment is for illustrative purposes only and forms no part of the claimed design.
